[57] ABSTRACT

A wrist watch having a quartz crystal time standard oscillator driving a pulse shaper circuit including counters for reducing the frequency of the signal from said oscillator to a time-keeping frequency for application to an electro-mechanical converter. A quick-feed correcting circuit operated by a manual operating switch corrects the second hand indication.

FIG.2

QUARTZ CRYSTAL WRIST WATCH

BACKGROUND OF THE INVENTION

This invention relates to time correction of a quartz crystal wrist watch having an electro-mechanical converter such as a pulse motor operated by low frequency driving signals of the order of several Hz or less.

Quartz crystal wrist watches have high accuracies, their monthly error being on the order of ± 5 seconds. For this reason, the time indication of such watches is seldom incorrect. However, because of the accuracy involved, wearers become anxious about errors within the range of several seconds which arise after long use and may be eager to correct such errors. In conventional quartz crystal watches, the correction of such small errors, if the error was a lag, required stopping the watch once, advancing the minute hand, and resetting the watch. This complicated procedure detracts from the otherwise valuable high accuracy provided by such watches. By the arrangement in accordance with the invention, means is provided so that correction of the second hand can be readily accomplished by the operation of a single manual switch.

SUMMARY OF THE INVENTION

Generally speaking, in accordance with the invention, a quartz crystal wrist watch is provided having a quartz crystal time standard oscillator for producing a high frequency time standard signal, an integrated pulse shaper circuit means including counters for reducing the frequency of said time standard signals to a low frequency timing signal, and an electro-mechanical converter means for driving the time keeping apparatus of the watch in response to said time keeping signal. A manual correcting switch and a quick-feed correcting circuit operated by said correcting switch are provided for the selective application of pulses to said electro-mechanical converter means for correcting the second hand of the watch.

The correcting circuit means may include a monostable multivibrator. Said correcting switch is also connected so as to serve as a preset switch for a counter circuit of said pulse shaper means, when operated.

Accordingly, an object of this invention is to provide means for insuring an easy and sure correction of the second hand in a quartz crystal time piece.

Still other objects and advantages of the invention will in part be obvious and will in part be apparent from the specification and drawings.

The invention accordingly comprises the features of construction, combination of elements, and arrangement of parts which will be exemplified in the construction hereinafter set forth, and the scope of the invention will be indicated in the claims.

BRIEF DESCRIPTION OF THE DRAWINGS

For a fuller understanding of the invention, reference is had to the following description taken in connection with the accompanying drawings, in which:

FIG. 1 is a block and schematic diagram of the electric circuitry and time indication mechanism of a quartz crystal wrist watch in accordance with the invention;

FIG. 2 is a waveform diagram showing the current waveforms at five locations in the circuit of FIG. 1.

DESCRIPTION OF THE PREFERRED EMBODIMENTS

Referring now to FIG. 1, the quartz wrist watch depicted consists of an oscillator including quartz crystal X and an inverter I₁ which produces a high frequency time standard signal. This high frequency time standard signal is applied to the IN terminal of pulse shaper C. Said pulse shaper consists of a series of divider circuits for reducing the frequency of the high frequency time standard signal from the oscillator to low frequency timing signals at output terminals OUT₁ and OUT₂. The output from output terminal OUT₁ is applied through inverters I₂ and I₃ to one end of motor driving coil L. The output of output terminal OUT₂ is applied through NOR gate NR₁ and inverter I₄ to the other end of said motor driving coil. The current i passes through said driving coil.

Where the frequency of the time standard signal is

20 16.384 kHz, pulse shaper C may have 15 binary counter stages. The waveforms for such an embodiment are depicted in FIG. 2. As shown therein, the motor driving current i consists of alternating pulses at one second intervals to alternately generate north and 25 south poles in stator S. Rotor RT is polarized into six poles as shown in FIG. 1, so that said rotor is turned by 60° every 1 second to rotate a fourth wheel and pinion to which the second hand is fixed.

The quick-feed circuitry in accordance with the invention is depicted in FIG. 1. Specifically, a monostable multivibrator consisting of NOR gate NR₂, capacitor C, resistor R and inverter I₅ is connected between a correcting switch SW and one of the inputs to NOR gate NR₁. The inputs to NOR gate NR₂ consists of the signal from switch SW and a feedback signal from the output of inverter I₅. The signal applied to NOR₁ is designated OUT₃. Resistor R and capacitor C determine the time constant of operation of the multivibrator. Switch SW is also connected to terminal PR of pulse shaper C, which terminal is connected so as to preset one of the counters of the chain of counters in pulse shaper C each time switch SW is closed.

Accordingly, when correcting switch SW is closed, an output voltage OUT₃ from the multivibrator is generated and a current pulse of the same polarity as the output from terminal OUT₂ of pulse shaper C is applied to motor driving coil L. The above mentioned counter of pulse shaper C is preset at the same time. If correcting switch SW is opened immediately, an output voltage is generated at terminal OUT₁ of pulse shaper C and a current pulse of reverse polarity to the pulse generated when said switch was closed flows through inverters I₂ and I₃ to driving coil L. Thus, repeated opening and closing of correcting switch SW advances rotor RT by 120°, corresponding to two seconds. On the other hand, if the operation of the watch is to be stopped, the correcting switch SW is maintained in the closed position. In this manner, correction of the setting of the second hand of the quartz crystal wrist watch may be readily accomplished.

In the preferred embodiment, the pulse width of the signal OUT₃ is made equal to the pulse width of the signal at output OUT₂. To prevent overlap between outputs OUT₁ and OUT₃, a capacitor is connected in parallel with switch SW. The foregoing circuitry can be formed from complementary field-effect transistors, with the exception of a few exterior parts such as the

capacitors, so as to limit the power drain. The pulse shaper C may be formed completely from such complementary field-effect transistors. If this approach is utilized to produce monolithic integrated circuits IC, a strong driving signal may be produced in a compact quartz crystal watch.

It will thus be seen that the objects set forth above, and those made apparent from the preceding description, are efficiently attained and, since certain changes may be made in the above construction without departing from the spirit and scope of the invention, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

What is claimed is:

1. A quartz crystal wrist watch comprising quartz crystal oscillator means for producing a high frequency time standard signal; pulse shaper circuit means for receiving said high frequency time standard signal; a time indication drive train including a second hand; an electro-mechanical converter means for driving said time keeping drive train and second hand in response to said timing signals; a manual correcting switch; and quick-feed correcting circuit means for applying a time correction pulse to said electro-mechanical converter in response to the operation of said correcting switch for advancing said second hand an incremental distance, said pulse shaper circuit means including a plurality of counter stages, said correcting circuit means being adapted to operatively connect said correcting switch

35

to at least one of said counter stages for applying a pre-setting signal to said counter stage in response to the operation of said correcting switch, said correcting circuit means being adapted so that a time correcting pulse is applied to said electro-mechanical converter means when said correcting switch is closed, and the counter to which said correcting switch is connected is preset when said correcting switch is closed.

2. A quartz crystal wrist watch comprising quartz

10 crystal oscillator means for producing a high frequency time standard signal; pulse shaper circuit means for receiving said high frequency time standard signal; a time indication drive train including a second hand; an electro-mechanical converter means for driving said time keeping drive train and second hand in response to said timing signals; a manual correcting switch; and quick-feed correcting circuit means for applying a time correcting pulse to said electro-mechanical converter in response to each operation of said correcting switch for

15 advancing said second hand an incremental distance, said correcting circuit means including a monostable multivibrator circuit means intermediate said correcting switch and said electro-mechanical converter means.

20 3. A quartz crystal wrist watch as recited in claim 3, wherein said electro-mechanical converter includes a driving coil, said pulse shaper circuit means having first and second output terminals for producing pulses of opposite polarity, and including gate means for receiving a signal from the second of said pulse shaper circuit means output terminals and from said monostable multivibrator circuit means, the pulse output of said second output terminal and said monostable multivibrator circuit means being of the same polarity.
